(57) **CLAIM**

The ornamental design for an apparatus for processing biological fluids, as shown and described.

DESCRIPTION

FIG. 1.1 is a front perspective view of the apparatus for processing biological fluids;
FIG. 1.2 is an enlarged partial front view thereof;
FIG. 1.3 is an enlarged partial front view thereof;
FIG. 1.4 is an enlarged partial front perspective view thereof;
FIG. 1.5 is a front perspective view thereof; and
FIG. 1.6 is a side perspective view thereof.
In the drawings, the portions of the apparatus for processing biological fluids shown in broken lines form no part of the claimed design.
